UNITED STATES PATENT OFFICE

HARRY E. KINGSBURY, OF KEENE, NEW HAMPSHIRE

TOY AIRPLANE

Application filed June 19, 1929. Serial No. 372,128.

This invention relates to improvements in toy airplanes, and more particularly concerns details of construction and assemblage of such devices.

One of the objects of the present invention is to provide a toy airplane having a light body portion with its members rigidly assembled, and to which the undercarriage, wings, elevator and rudder members may be quickly and elastically attached, and from which they may be disconnected for ease in packing.

Another object of the present invention is to provide improvements in the undercarriage construction and assemblage with respect to the body which enables a simple and cheap manufacture of this portion, and an ease in mounting upon the body, along with a functioning elasticity in such manner that when the plane comes to ground, the underframe and associated parts yield to the impact without breakage.

A further object of the invention is the provision of means for constructing and mounting the wings upon the body by which they are rigid and protected against accident, while being capable of adjustment with respect to the angle of incidence, and yet are elastically mounted upon the body to prevent breakage upon encountering an obstacle during flight.

Still another object of the invention is an improved elevator and rudder assembly which is elastically mounted upon the body and adjustable so that the parts may yield as necessary, and may be disassembled or folded for packing, and in which the rudder member may be adjusted to determine the direction of flight.

Another object of the present invention is to provide a simple and cheap construction of the propeller.

Another object of the invention is to provide simple and rigid brace means for the body to enable it to support the strain of the band motor and of impact of any part of the device with the ground or an obstacle.

Still another object of the invention is to provide a simple and cheap mounting for a rear wheel, so that the toy airplane will re-

quire less power and less distance of travel when running for a take-off.

With these and other objects in view as will appear in the course of the following specification and claims, illustrative examples of the construction employed have been set forth on the accompanying drawings, in which:

Figure 1 is a plan view of the assembled airplane.

Fig. 2 is a corresponding side elevation.

Fig. 3 is a vertical longitudinal section substantially on line 3—3 of Fig. 1, upon an enlarged scale and showing the propeller mounting, and the undercarriage mounting.

Fig. 4 is a similar vertical longitudinal section substantially on the line 4—4 of Fig. 1 and showing the wing construction and mounting.

Fig. 5 is a similar vertical longitudinal section on line 5—5 of Fig. 1 through the elevator plane.

Fig. 6 is a corresponding vertical longitudinal section substantially on line 6—6 of Fig. 1 through the body and central portion of the wings.

Fig. 7 is a perspective view indicated in partial section of the edge protector.

Fig. 8 is a bottom plan view of a reinforcing rib for the wings.

Fig. 9 is a detailed perspective view of a portion of the undercarriage assembly.

Fig. 10 is a vertical transverse section substantially on lines 10—10 of Figs. 1 and 5.

Fig. 11 is a plan of a modified form of rudder construction, mounted on the elevator.

Fig. 12 is a perspective view of a modified form of undercarriage assembly.

In the drawings, the body comprises the two spars 10, 11 which extend longitudinally thereof and are slightly bowed from end to end so that their greatest distance apart is substantially at the point of attachment of the wings. At the front ends of the spars 10, 11 are joined by a sheet metal clip 12 which is formed by folding a sheet of metal to provide sleeves 13 fitted over the ends of the respective spars 10, 11, the whole clip being bent into U-shape as seen in Fig. 1, with the central portion reinforced by the flanges 14 and

provided with an aperture for the passage of the driving shaft 15 for the propeller. The sleeves 13 at their rear ends have each a projecting ear 16 spaced from the lower surface 5 of the respective spar 10 or 11. Intermediate the length of the spars they are provided with a cross brace 17 likewise formed from sheet metal with reinforcing flanges and provided at the ends with the sleeves 18 10 which are fitted about the respective spars 10, 11 and preferably are held thereto by indentations 19 which depress the inner wall of the sleeve 18 into the structure of the respective spar. The connecting part of the metal brace 17 is curved downward to afford clearance for the band motor M. The forward ends of the sleeves 18 are provided with ears 20 which are spaced from the lower surfaces 15 of the spars 10, 11. 20 The rear ends of the spars 10, 11 are connected by a clip 21 having the sleeves 22 formed at the ends thereof to receive the spars 10, 11 and be fixedly connected thereto. The ends of the sleeves 22 project beyond the 25 ends of the spars, and the inwardly directed faces of the clip are at this point perforated to receive the axle pin 23 of the rear wheel R, which is received between the sleeves 22 in the U-shaped clip 21 (Fig. 1), while the walls of 30 the sleeves 22 are crimped down to prevent lengthwise movement of the pin 23. The central portion of the U-shaped clip 21 is provided with two apertures through which passes the fixed rear stay 24 for the band motor M, as shown in Fig. 5, whereby this stay is prevented from movement about its own axis.

The undercarriage comprises the axle shaft 25 which passes through the front wheels F 40 so that these wheels may rotate freely therearound, and is provided with bent ends to prevent the wheels from coming off this axle. The undercarriage strut construction comprises a single piece of wire, substantially 45 symmetrical about the central vertical and longitudinal axes of the airship. The forward ends of the strut wire are bent inward and then upward to fit closely around the spars 10, 11 (Figs. 1 and 3), being received 50 between the ears 16 and the respective spar 10 or 11. The strut wire extends relatively outwardly, rearwardly and downwardly from its forward end connection, to form the front struts 26, and then is provided with a 55 plurality of convolutions 27 loosely surrounding the axle 25 so that the axle may turn within these convolutions as in a bearing. From these convolutions the strut wire extends upwardly, rearwardly and inwardly to form the 60 rear struts 28, at the upper ends of which the wire portions just described are joined by the integral bridge 29 having a relative downwardly convex curvature to avoid the band motor M, and being provided with loops to 65 fit between the ears 20 and the respective spars

10, 11 (Figs. 1 and 3), the angle between the planes of the curved portion 29 and of the rear struts 28 being such as to prevent lateral movement of the strut wire at its rear end. A retaining or stop member 30 is likewise 70 formed of wire with symmetrical ends each comprising a bent portion 31 terminating in an eye 32 fitting about the axle 25.

The wire strut member is formed so that the convolutions 27 act as a torsion spring to 75 force the strut members 26, 28 relatively away from one another in Fig. 2, so that when the undercarriage is removed from the body, it preferably has the struts 26 and 28 substantially in a plane for easy packing. To assemble the undercarriage to the body, the struts 26, 28 are compressed beyond the position shown in Fig. 2, and the rear bridge 29 is slipped between the ears 20 and the spars 10, 11. The front ends 26a are then slipped 80 between the respective clips 16 and spars 10, 11. The torsional effect of the convolutions 27 will now hold the undercarriage fixedly to the body. In alighting on the ground, the weight of the body coming upon the struts 26, 28 will force the convolutions 27 downward slightly, with a springy yielding of the 85 axle 25: the stop member 30 prevents the spreading of the convolutions 27 laterally under such conditions and thus prevents a binding or braking of the front wheels F. The undercarriage construction has been 90 described and claimed in my divisional application Ser. No. 419,112 filed Jan. 7, 1930, which resulted in Patent No. 1,784,730, dated December 9, 1930.

The wing assembly comprises the two symmetrically formed wing surfaces 33, 34 which are concaved upwardly as usual, and are preferably formed of thin veneer wood. The front edges of these wings are protected by reinforcing strips 35 formed of sheet metal in channel shape to fit around the front edges of the wings and being provided with the rearwardly extending lugs 36 having in-turned prongs 37 biting into the wood of the wing structure itself. The curvature of the wings is preferably maintained by the provision of channel-shaped sheet metal ribs 38 (Figs. 2 and 8) extending for the full width of the wing and having ends 39 bent over the edges of the wings to hold these ribs fixedly in position and to produce and maintain the desired concavity or air-foil suction.

The two wings 33, 34 are joined at their centers at a diedral angle by the thin sheet metal plates 40, 41 which fit over and under the surfaces of the wings. One of these plates is forced out of plane to form the eyelets 42 which pass through corresponding apertures in the wings and in the other plate, and are clinched upon the other plate, as shown in Fig. 6. This produces a very simple, light and cheap assemblage. At the front edge of the wing, it is likewise provided with an ad-

justing plate 43 of sheet metal, which conforms to the shaping of the lower surface of the wings at this point, and to the dihedral angle therebetween and is provided with a downwardly and rearwardly extending flange 44 to stiffen the same and to support this edge of the wing slightly above the rear edge at all times. It is preferred (Fig. 6) to cause the metal eyelet 42a formed at the 10 front hole to pass through an aperture in the plate 43 and thus hold the latter in position in a simple manner.

Light wood blocks 45 are loosely mounted transversely across the spars 10, 11 at a 15 distance apart which is substantially identical with the width of the wings. This separation is maintained by the wing block wires 46 which are imbedded at their ends in these blocks, and have a slight upwardly convex curvature and resiliency tending to draw the blocks close together. Rubber bands are employed to hold these blocks to the respective spars 10 and 11, the endless band passing with a loop 46a beneath a respective 20 spar, with an extension 47 substantially upward and over a block 45, thence substantially parallel to the spar in a length 48, over and around the other block 45 and being completed by a loop 49 beneath the spar. It will 25 be noted that since the rubber band is under elastic tension, it also tends to pull the blocks 45 slightly closer together, thus engaging them against the edges of the wing and holding the wing in an adjusted position.

30 The elevator 50 is preferably a thin sheet of veneer wood cut to appropriate shape and mounted loosely upon the top of the spars 10, 11. The rudder 51 is likewise preferably of thin veneer wood cut to a desired shape and 35 provided at its bottom with a sheet metal reinforcing member comprising the two lateral faces 52 which tightly clamp the lower edge of the rudder and are provided with the ears 53 in which indentations may be 40 formed to lock the side plates 52 in position. These side plates extend around the lower edge of the rudder in integral channel form, and project front and back beyond the edges 45 of the rudder to form the lugs 54, 55. The 50 upper edges of the plates 52 at these points are bent over to form the curls 56 which prevent cutting of the rubber securing bands, while near these curls 56, the plates 52 are formed with the downwardly and outwardly projecting feet 57 which rest upon the elevator 50 to support the rudder in upright position. The elevator and rudder may be held elastically in position upon the spars and with 55 respect to one another by two rubber bands. 60 Each of these bands is located to have a portion 58 over the top of the elevator, terminating in loops 59, 60 around the outside and beneath the respective spars 10, 11 and thence inwardly and upwardly in a portion 61 passing over the adjacent curl 56 and thence 65

across the front or back of the rudder and extending along the rudder in a run 62. It will be noted that these bands are disposed substantially symmetrically, and operate by the portions 58 directly to hold the elevator 70 upon the spars, while preventing a movement of the elevator about a relatively vertical axis, and by the portion 62 operates upon the rudder to hold the latter upright upon the elevator, and to further assist in holding the 75 elevator upon the spars. The rudder may be easily rotated about an axis passing through the lower portion of the plates 52 into a position parallel to the elevator 50 for 80 packing, without removing or disturbing the rubber bands.

In the modified form of rudder construction shown in Fig. 11, the elevator 50a again serves as the rest for the feet 57a of the channel member providing the two plates 52a 85 between which is clamped the rudder proper 51a. In this instance, however, the front end of the channel terminates substantially flush with the front end of the rudder 51a, 90 while the rear end of this channel terminates flush with the lower portion of the rear end of the rudder 51a. The two rubber bands are again employed to hold the elevator 50a and the rudder 51a in position, these bands being 95 placed beneath the spars 10, 11 and brought up inside and outside of these spars so that the elevator can be slipped between the upper portions 58a of these bands, and then the feet 57a of the rudder worked in between.

100 In either case, the rudder may be adjusted about a relatively vertical axis by displacing its front end and rear end laterally, whereby the airship may be caused to travel in a straight-away or curved flight.

105 The propeller is formed from two identically shaped pieces of metal 100 and 101 which for the major portion of the periphery of each has a rebent stiffening bead 102. Adjacent the axis, however, this bead is omitted,—for example, on plate 101 in Fig. 1— 110 so that the bead 102 on plate 100 may lap over the plate 101. It will be noted that the plate 101 increases in size in each direction from the axis of the propeller, so that the bead 102 serves to hold the two plates 100 and 101 together. The symmetry of this arrangement is indicated in Fig. 2, where the plate 101 has the bead 102a fitting over the end 100a of the plate 100. Each plate is formed, for a distance in each direction from the axis, with a bulging elevation 103 which serves to reinforce and stiffen the propeller at this point. In this axis, the two plates 100, 101 are so constructed and arranged as 115 to receive the front stub shaft or spindle 15 for the band motor M: the extreme front end 15a of this spindle being rebent for the purpose of preventing the spindle 15 being drawn rearward by the band motor, and for 120 securing a driving relationship between the 125 130

spindle 15 and the propeller. The rearward end of the spindle 15 is likewise formed with a loop 15b, preferably covered with a piece of rubber tubing, to prevent abrasion and cutting, to receive the front end of the band motor M. This band motor extends substantially in the line of the spars 10, 11. It is carried at its rear end about the hook 104 of the rear stub shaft 24. The propeller construction has been described and claimed in my divisional application Ser. No. 424,982, filed Jan. 31, 1930.

In Fig. 12 is shown a modified form of construction of the axle assembly indicated in Fig. 9. In this modified form, the axle 25a is formed with rebent and offset ends to receive the wheels, this rebent portion 31a itself providing a stop for limiting the spreading movement of the coils 27 joining the wire struts 26 and 28.

It is obvious that the invention is not limited to the forms of construction described and shown, but that such may be modified in many ways within the scope of the appended claims.

What I claim as new and desire to secure by Letters Patent is:

1. In a toy airplane, body spars, transverse wood blocks, wire members holding said blocks spaced apart and permitting a resilient movement of the blocks away from one another, and rubber bands extending around the respective spars, over one of the blocks, over the other block and then around the spars again whereby to provide an elastic mounting of the blocks on the spars.

2. In a toy airplane, body spars, wood blocks mounted transversely of the spars, a main wing mounted loosely between the blocks and frictionally engaged therewith, and rubber bands passing around the spars and blocks to establish a resilient frictional pressure against the wing to hold it in adjusted position.

3. In a toy airplane, a main wing comprising a right hand and a left hand part, upper and lower metal plates to hold the parts together, one of said plates having holes, the other of said plates having eyelets passing through holes in the wing and said holes in the other plate and being clinched upon said other plate whereby to hold the parts and plates rigidly together.

4. In a toy airplane as in claim 3 in which a bracket of metal is provided to determine an angle of incidence for the wing, said metal bracket having holes therein, the eyelets of said other plate passing through said holes whereby said bracket is fastened rigidly to said wing.

5. In a toy airplane, body spars, a main wing mounted on said body spars and including a metal bracket extending downward from the front edge of said wing and adapted to engage said spars whereby to determine an

angle of incidence, and means to fasten said wing to said spars.

6. In a toy airplane, body spars, an elevator plane, a rudder, lateral projecting rudder feet resting on said plane and movable laterally relative to the plane, and elastic means engaging said spars and rudder feet to hold said rudder, elevator and spars together.

7. In a toy airplane, body spars, an elevator plane resting flat against the body spars, a rudder having laterally projecting feet resting against said plane and forwardly and rearwardly extending projections, said rudder when its feet and projections being movable to the plane and spars, and elastic means engaging said spars and said rudder feet and projections to hold said rudder, elevator and spars together.

8. In a toy airplane, body spars, an elevator plane resting on said body spars, a rudder, laterally projecting rudder feet resting on said elevator plane, said rudder and elevator plane being movable relative to one another and to the spars, and elastic means passing over the rudder feet and elevator plane and beneath the spars for holding said rudder, elevator plane and spars together.

In testimony whereof, I affix my signature.
